SYNCHRONIZING SYSTEM

Friedrich Klaiber, Berlin, Germany, assignor to
 Telefunken Gesellschaft für Drahtlose Tele-
 graphie m. b. H., Berlin, Germany, a corpora-
 tion of Germany

Application May 12, 1931, Serial No. 536,714, and
 in Germany April 25, 1930

2 Claims. (Cl. 178—69.5)

The present invention relates to a means for picking up electrical impulses in connection with synchronizing means of the kind specially required for the purposes of television work. In television transmissions the electrical potentials which correspond to the picture units or elements produced at the sending end by means of a Nipkow disk, are fed from the radio frequency receiver or the audio frequency stage thereof, for instance, to a glow discharge or gaseous-conduction lamp or some other kind of light-conversion device, such as a Kerr cell, and the luminous fluxes produced by the latter are then recomposed to create the desired picture by the aid of a Nipkow disk or other suitable scanning instrumentality. The procedure preferably is so arranged that for the purpose of insuring synchronous running of both Nipkow disks, a frequency is transmitted from the sending equipment (most conveniently by means of the same carrier frequency or over the same line) to the receiver apparatus, and this frequency is suitably adapted to serve for the control of the synchronizer apparatus. The output circuit of the receiver equipment thus contains a synchronizing frequency in addition to the potentials corresponding to the picture units or elements and it is this frequency which is arranged to control or insure the synchronous operation or drive of the Nipkow disk in the receiver equipment. The chief point is to supply the synchronous driving device with a suitable synchronizing frequency in a convenient way.

According to the present invention, the potentials operative in the output circuit of the audio frequency tube of the receiver apparatus and coming in from the transmitter equipment control the light-conversion device in television receiver sets. This device may, for example, be a glow-discharge or gaseous conduction lamp. According to a modified form of device, part of these potentials coupled by potentiometer means may control at the same time a discharge vessel, the latter in turn serving to actuate a synchronizing means after all other frequencies (outside the synchronizing frequency) have been filtered out. According to the invention, the potentials of the output circuit of the receiver apparatus most suitably are simultaneously fed both to the light-conversion device as well as to the grid of a triode tube, the amplified plate current thereof after having been rid of frequencies not required for synchronizing being fed to the synchronizing device.

Preferably in the plate circuit of the thermionic tube controlled by the output-circuit potentials

of the receiver, there are provided according to this invention filtering means of a kind known in the prior art so that there will be imparted to the grid of the next tube whose plate current serves to actuate the synchronizing device, only potentials having the frequency intended for synchronizing. In this manner conditions are made such that the potentials controlling the light-conversion device will not be distorted by the means provided for filtering the synchronizing frequency, and above all that absorption of the synchronizing frequency from the output circuit of the receiver will not be attended with energy consumption.

According to one object of this invention, the synchronizing frequency preferably consists of a frequency inevitably resulting at the sending end from the process of scanning the picture, predominantly a frequency which results by reason of the fact that darkness prevails for a short while between the instant of slipping over a perforation in the Nipkow disk at the end of a line and the entrance of the next hole of the next line into the picture surface. For this purpose, the picture window may be enlarged somewhat in width than what would correspond to the breadth or distance between two holes of the Nipkow disk. The frequency thus obtained is equal to the product of the picture unit number per second and the number of the lines, in other words, equal to 375 Hertz (cycles) if the Nipkow disk at the sending end revolves 12½ times per second, and if it is provided with 30 holes. Accordingly, filter means should be provided in the plate circuit of a thermionic tube serving for the production of the synchronizing means (frequency) or in the grid or plate circuit of an amplifier tube associated therewith, said filters being designed to permit the propagation only of this particular frequency.

Now, according to the invention the ensuing potentials of synchronizing frequency are fed to two windings being respectively fitted upon the two pole-shoes of an iron-core. These pole-shoes in well known manner are disposed opposite the keeper of a medium frequency generator which is driven by a motor. The windings are used at the same time to tune the output circuit of the tubes controlling the synchronizing device to the synchronizing frequency, and to complete or perfect the filtering of the latter. The discharge vessel serving for the production of the synchronizing frequency, and the light-conversion device, according to this invention, are fed from a joint potential-source, most preferably from the net-

work potential, by way of a rectifier in case of an alternating current supply line. The direct current circuit of the assembly is separated from the direct current circuit of the output or power tube 5 of the receiver apparatus. The direct current circuit of the glow discharge tube suitably includes a variable resistance so that, in order to insure maximum differences of brightness, the direct current potential fed to the gaseous-conduction lamp may be so set that the difference resulting from the direct current potential and the crest value of the alternating current potential will always be just higher than the extinction potential of the said tube or lamp.

10 The light conversion device conjointly with the tubes to produce the synchronizing frequency, the means establishing connection with the network or supply line and a change-over switch for making connections for radio or picture transmission or reception are disposed inside a joint casing.

15 One embodiment of the invention is illustrated in Figs. 1 to 4, wherein: Fig. 1 shows the assembly of the arrangement; Fig. 2 illustrates the key diagram; Fig. 3 illustrates one form of synchronizing device in further detail; and Fig. 4 represents a modification of Fig. 3 for filtering the synchronizing frequency.

20 Referring to Fig. 1, 1 denotes the radio frequency receiver comprising the last audio frequency stage tube 2 together with output terminals 3 and plate potential 4 bridged by a condenser. The filament of tube 2 is grounded, for instance. 5 is a casing in which the television outfit of this invention is accommodated. Opposite the Nipkow disk 6a is a gaseous-conduction lamp 6 being indicated only schematically. This lamp is fed with direct current potential from the voltage source 7 (supply-line connection means). The output terminals 3 of the receiver 1 and the input terminals 8 of the television receiver 5 are inter-connected, for instance, by means of a two-conductor cord. By means of the change-over switch 9 the output potentials of tube 2 may be applied to the loudspeaker 10 or terminals 11. United with terminals 11 is the television receiver apparatus. The alternating current potentials acting across the resistance 12 from tube 2 are supplied by way of the blocking condenser 13 to gaseous-conduction lamp 6, and by way of the blocking condenser 14 to the tube 15 serving for filtering out the synchronizing frequency which is likewise supplied from the potential source 7. As to the rest, all of these connections are diagrammatically indicated in key diagrams of Fig. 2.

25 Gaseous-conduction lamp 6 and the tubes 15 and 16 serving for the production of the synchronizing frequency are fed with the necessary potential from the supply-line 17 by the aid of transformer 18 and rectifiers 19. Numerals 20, 21 denote windings for the heating of the rectifier 19 or the tubes 15, 16. The filter circuit consisting of choke coils 22, 23, and the condenser 24 serves for smoothing the potential supplied to the gaseous conduction tube and the plate potential for the tubes 15, 16. The gaseous conduction tube is fed with direct current by way of resistance 25 and the variable resistance 26. In the negative lead for the gaseous conduction lamp there are further included potentiometric resistances 27 for tapping the grid biasing potential for the tube 15. The latter is fed with grid biasing potential by way of resistances 28 and 29. In order to obtain definite plate potentials for the tubes 15 and

16, there are also provided the series resistances 30 and 31 because relatively high potentials are required for the gaseous conduction tube. Numerals 32 to 36 represent shunting capacities. The plate circuit of tube 15 is coupled by means of the resistance 37 and capacity 38 with the grid of tube 16, the tube 16 serving at the same time for the amplification of the synchronizing frequency. Between the grid and the filament of tube 16 is connected an oscillation circuit tuned to the synchronizer wave and comprising inductance 39 and capacity 40. This oscillation or tuned circuit constitutes a high reactance only for the synchronizing frequency, while a very low one for all other frequencies.

20 Included in the plate circuit of the tube 16 is a transformer 41; the secondary winding of the same is arranged in parallel with condenser 42, while being in series relation as shown with the windings 43 and 44 of the synchronizing device which may be connected either in parallel or series. The circuit consisting of the secondary winding of the transformer 41, the capacity 42 and the windings 43, 44, is so tuned (potential-resonance fashion) that in the plate circuit of tube 16 a high resistance is transferred only for the synchronizing frequency, with the result that the windings 43, 44 substantially are energized only by the synchronizing frequency. The synchronizing device is illustrated in more detail in Fig. 3.

25 Referring now to Fig. 3, 45 denotes the armature of a synchronous generator which is propelled by a motor (not shown). Opposite the said synchronous wheel or armature 45 are mounted the pole-shoes wrapped with the windings 43 and 44 in a way as shown in the drawing. The iron body or core 46 is further provided with a winding 47 which must be fed with direct current to obtain a desired flux of definite value, preferably from the potential of the rectifier 19.

30 An arrangement of the type shown by Fig. 4 has proven particularly suitable for the filtering out of the synchronizing frequency from the plate current of the tube which controls the synchronizing device including windings 43, 44. The plate circuit of tube 76 as shown by Fig. 4 contains in series the windings 43, 44 and the condenser 48. This branch of circuit is tuned to the synchronizing wave series-resonance fashion. Plate potential is supplied to the tube 76 by way of the choke coil 49 which by the aid of the capacity 50 is likewise tuned to the synchronizing frequency.

35 To prevent synchronizing frequency from flowing off by way of the direct current winding 51 of the synchronizing device, a choke coil 46 tuned to the synchronizing frequency by the aid of condenser 47 may be inserted in the lead connecting the winding and the source of potential so that the fly-wheel circuit 46, 47 acts like a stopper for the synchronizing frequency.

40 Other modifications and changes may suggest themselves to those skilled in the art to which the invention relates, and I, therefore, believe myself to be entitled to make and use any and all of such modifications as fall fairly within the spirit and scope of the hereinafter appended claims.

45 Having now described my invention, what I claim and desire to secure by Letters Patent is the following:

50 1. A synchronizing system for television comprising an image reproducing device, means for rotating the image reproducing device and a synchronizing device for controlling the rotation of

- the driving element for rotating the image reproducer, means for receiving combined image and synchronizing signals, means for supplying the received signals to said image reproducing device 5 to produce electro-optical reproductions thereof, a vacuum tube circuit connected with said synchronizing device, means for supplying the received signals also to said vacuum tube circuit, a portion of said vacuum tube circuit tuned to 10 said synchronizing signals, and means including a portion of the said synchronizing device connected with the said vacuum tube circuit for separating said synchronizing signals from said image signals.
- 15 2. A synchronizing system for television comprising means for receiving combined image and synchronizing signals, a rotary synchronizing element for insuring proper positioning of the electro-optical effects resulting from the received image signals, said synchronizing device having windings adapted to be energized by said synchronizing signals, a vacuum tube circuit having a portion thereof tuned to the synchronizing signal connected with said synchronizing device windings and with the source of said received image and synchronizing signals whereby said windings are utilized as a filter device connected with said vacuum tube circuit to separate the synchronizing signals from the image signals and cause the synchronizing signals to exert a speed correcting impulse upon said windings. 80 85 90
